UNITED STATES PATENT OFFICE.

PEARL A. LEWIS AND HENRY N. FAAS, OF SPRINGFIELD, OHIO, ASSIGNEES TO THE AMERICAN SEEDING MACHINE COMPANY, OF SPRINGFIELD, OHIO, A CORPORATION OF OHIO.

CULTIVATOR.

1,093,789.

Specification of Letters Patent.

Patented Apr. 21, 1914.

Application filed April 16, 1912. Serial No. 691,133.

To all whom it may concern:

Be it known that we, PEARL A. LEWIS and HENRY N. FAAS, citizens of the United States, residing at Springfield, in the county 5 of Clark and State of Ohio, have invented certain new and useful Improvements in Cultivators, of which the following is a specification.

This invention relates to improvements 10 in cultivators and more particularly to improvements on the machine illustrated in Letters Patent of the United States No. 961,762, issued June 21st, 1910, to H. E. Dodson and Henry N. Faas.

One of the objects of the invention is to 15 provide means for so connecting the respective gangs of cultivating disks to their supports that each gang may be quickly and readily moved from one of its operative positions to the other without the necessity of removing any parts or disconnecting the parts in any particular; it being understood that one of the operative positions of the disks is that in which they throw the 20 earth away from the plants, while the other operative position is for causing the disks to hill toward the plants.

A further object is to simplify the construction and mode of operation of machines of the character referred to.

In the accompanying drawings,—Figure 1 is a sectional view through a portion of the support for one of the disk gangs showing the manner of adjustably securing 35 the parts thereof together. Figs. 2 and 3 are details of the same. Fig. 4 is a rear view of a portion of the machine showing the gang of disks in one position of operation. Fig. 5 is also a rear view showing 40 the disks in a different position of operation.

Like parts are represented by similar characters of reference in the several views.

In the said drawings, 1 represents the 45 rear rail of the frame of the machine, which, together with the brackets 2 connected at the respective ends thereof, forms an arch-shaped axle-frame. The ground-wheels 3 are pivotally connected to this arch-shaped 50 frame, each of the axles 4 having an upturned portion 4^a journaled in perforated ears or lugs 5 projecting laterally from the bracket 2.

The cultivating members are in the na-

ture of two gangs of disks arranged on opposite sides of the machine. The disks 8 of each gang are secured to a shaft which is journaled in bearings at the lower end of the yoke 10 in the usual way, which yoke has rigidly secured at its upper end a bearing plate 11. This plate 11 is pivotally connected, through the medium of a bolt 12, with a coöperating plate 13; said plate 11 having a centrally-arranged boss or projection 14 over which the plate 13 fits and also 60 having at its outer edge an upturned rim 15 upon which said plate 13 rests. The bolt 12 extends through the boss 14 and also through the yoke 10 and has a washer 12^a overlying the plate 13 so as to pivotally 65 connect the two plates together. As in the former patent referred to, the plate 13 has an upwardly extending serrated portion 16 secured to the serrated face of a bracket 17 through the medium of the rod 18, the 70 lower bent end of which extends through perforations in the parts 16 and 17 and is screw-threaded to receive the nut 19 so as to clamp the parts firmly together. As in the former patent, the rod extends up through 75 perforated guides 20 extending laterally from a supporting head 21, adjustably secured to the bar 1 by set-screws 21^a, this support 21 also having pivoted thereto the usual lifting and presser lever 22 connected 80 to the bracket 17 by the rod 23, which rod carries the coil-spring 23^a interposed between the collars thereon so that pressure may be applied to the cultivating disks in 85 the usual way.

In the operation of cultivators employing disk cultivating members, it is necessary to be able to so position the disks that they will hill toward the plants or throw the earth away from the plants, depending upon 90 the conditions. One of the features of this invention is to provide means whereby each gang of disks may be so connected with its support that it may be quickly and readily moved from either one of these positions 100 of operation to the other without the necessity of removing or disconnecting any of the parts. To accomplish this, one of the bearing plates forming the connection between each gang of disks and its support, 105 such as the plate 11, is provided with two series of serrations or teeth, one series 25 being located in the rear edge of the rim 15

of said plate, and the other series 26 being located in the front edge of the rim 15 of said plate. Coöoperating with these serrations is a dog or pawl 27 on the plate 13, this pawl being located between two ears 28 on said plate and pivotally connected with said ears by a cotter pin 29. A coil-spring 30 located in a housing 31 projecting upwardly from said plate 13, normally 10 tends to hold said pawl in engagement with any one of the series of serrations; said housing being formed with a recess 32 to accommodate the pawl 27 when in the dotted line position shown in Fig. 1, to permit 15 its disengagement with said serrations. As a result of this construction, the gang of disks may be held either in the position shown in Fig. 4 to hill toward the plants, or may be turned to the position shown in 20 Fig. 5 to throw the earth away from the plants by simply raising the dog, and, by having the series of serrations on both the front and rear edges of the plate, it will be seen that the gang of disks may also be 25 adjusted to any desired angle with respect to the line of draft in either one of the aforesaid positions of operation.

Having thus described our invention, we claim:—

In a cultivator, a disk cultivating member comprising a yoke, a bearing plate secured to the upper end of said yoke, said plate having a centrally upwardly-extending projection and an outer upwardly-extending flange, a support, a plate connected with said support having a journal for said projection, means for pivotally connecting said plates together, a series of notches arranged in the front and rear of said flange respectively, and a spring-pressed dog carried by said support plate for engagement with said notches to hold said cultivating member in different positions of adjustment with respect to said support in both positions of operation of said cultivating member. 30 35 40 45

In testimony whereof, we have hereunto set our hands this 27th day of March 1912.

PEARL A. LEWIS.
HENRY N. FAAS.
